UNITED STATES PATENT OFFICE.

EUGENE A. KUEN, OF CINCINNATI, OHIO.

SINGLE-CONTROL MECHANISM FOR RADIO TUNING DEVICES.

Application filed May 14, 1925. Serial No. 39,178.

This invention is particularly designed to produce a single control mechanism for the instruments of a radio receiver, in which an object has been to simplify the tuning or setting of the cooperating condensers or similar adjustable devices by means of which the receiver is controlled to receive the desired signals from among the many signals of different wave length which may be in the air. 5

10 A further object is to produce such a single control mechanism for the several condensers or other instruments of a radio receiver, as will operate to secure their adjustment without lost motion, throughout the entire range 15 of the effective operation of these instruments, and with the greatest of ease of manipulation.

These and other objects are attained in mechanism described in the following specification and illustrated in the accompanying drawing in which: 20

Fig. 1 is a front elevational view of the panel of a receiver equipped with the invention described herein.

25 Fig. 2 is a rear view of the panel of the receiver, showing the mechanism embodying the features of novelty described herein.

Fig. 3 is a view similar to Fig. 2, but showing the mechanism in a different position.

30 Fig. 4 is an end elevational view of the receiver panel and attached instrument with the controlling mechanism.

Fig. 5 is a view similar to Fig. 4, but of a different instrument and the controlling mechanism. 35

In the example of receiver which has been illustrated as a type to which the invention may be applied, there has been chosen one which employs three variable condensers. By 40 way of further example the chosen arrangement is such that one plain variable condenser 6, see Fig. 5, is centrally located on the panel and is operated directly by a large dial 7 secured to the condenser shaft 8 which ex- 45 tends through the panel as is usual. To each side of the plain condenser a vernier type variable condenser is mounted, see Fig. 4, but only the vernier plates 9 are controlled separately by separate small control dials 10 and 50 11. The main plates 12 of the vernier condensers are controlled simultaneously with those of condenser 6 through the large dial 7 by means of the mechanism which constitutes the novelty of the invention described herein. 55

This mechanism, which is shown quite clearly in Figs. 2 and 3, consists of but very few and simple parts. On each condenser main shaft 13, 8 and 14, a double arm lever 15 is secured, preferably back of the panel and between it and the condensers mounted on it. 60 Attached to the upper arms 15^a of these levers 15 is the link 16, and attached to the lower arms 15^b of these levers is the lower link 17. The formation of these links is particularly adapted to permit the rotation of the condenser plates through a complete half circle 65 without interference with the condenser shafts or other parts of the apparatus. This is accomplished by providing extensions 18 on the links so that they will be completely 70 clear of the condenser shafts even when they are moved to the extreme positions shown in Fig. 3. Now as to the operation of the apparatus shown, it is quite obvious that the rotation of the single dial 7 will bring about 75 simultaneous operation of all the condensers, the action of the centrally located actuating lever being such that when it is rotated it will draw the links toward one another or will push them apart along a path describing an 80 arc of a circle, the extreme positions being shown in Figs. 2 and 3. Such simultaneous adjustment of the condensers may perhaps secure but an approximate setting to bring in 85 the desired station at full resonance. Therefore, in order to bring about the desired clear- 90 ness of reception there have been shown vernier condensers as the cooperating condensers, located on each side of the central condenser. These verniers, as is usual, consist 95 of the main section represented by the main plates 12 and the vernier plates indicated by numeral 9. The main plates of each vernier condenser are controlled in their adjustment by the main condenser shafts 13 and 14, while 100 the vernier plates are controlled by the vernier shafts 19 and 20 which extend through the hollow interiors of these main shafts and have the dials 10 and 11 mounted on their projecting ends which extend through the panel. 105 Thus, after the original setting of the main dial the clearing up of the reception of the desired signal is secured by adjusting the vernier controls 10 and 11.

Although there has been shown the specific 110 arrangement of one plain and two vernier condensers, this is merely by way of example and is intended to disclose one embodiment of the invention which consists of the links 16 and 17 and the connections by means of which they operate the instruments to be adjusted from a single source of control.

Having thus described the invention what is claimed is:

1. A mechanism for controlling simultaneously several tuning instruments in a radio receiver, comprising a lever attached to the shaft of each of said instruments, and a link connecting the levers, whereby when the shaft of one instrument is rotated all the instruments will be operated simultaneously, said link having extensions adapted to permit movement of the instruments throughout the entire range of their effective operation without interference of said link with any portion of said instruments at any point of the operation.
- 10 15 20 25
2. A mechanism for controlling simul-

taneously several tuning instruments in a radio receiver, comprising a lever attached to the shaft of each of said instruments intermediate the ends of the shaft, and a link connecting the levers, whereby when the shaft of one instrument is rotated all the instruments will be operated simultaneously, said link having extensions adapted to permit movement of the instruments through an angle of 180 degrees without interference of said link with said shafts at any point of the operation.

In testimony whereof I have hereunto affixed my signature.

EUGENE A. KUEN.
